UNITED STATES PATENT OFFICE.

WILLIAM C. STEWART, OF SWAMPSOFT, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

ASSEMBLING MACHINE.

Application filed September 14, 1917. Serial No. 191,469.

To all whom it may concern:

Be it known that I, WILLIAM C. STEWART, a subject of the King of England, residing at Swampscott, in the county of Essex and 5 State of Massachusetts, have invented certain Improvements in Assembling Machines, of which the following description, in connection with the accompanying drawings, is a specification, like reference characters on 10 the drawings indicating like parts in the several figures.

This invention relates to machines for assembling parts of boots and shoes upon their lasts preparatory to the pulling-over and 15 lasting operations. For the purpose of illustration, an embodiment of the invention is herein shown as applied to a machine of the type described in Letters Patent of the United States No. 1,356,510 granted October 20 26, 1920 on application of Hannah Ashton, executrix of the will of Orrell Ashton. It is to be understood, however, that the invention is not restricted to embodiment in a machine of the particular type disclosed in 25 said patent.

In the earlier machine, above referred to, mechanism is provided for inserting tacks into the shoe bottom through the flange of the counter or heel stiffener and into the heel 30 seat, the tacking mechanisms being carried to a point beyond the upstanding margin of the upper and the tacks inserted through the flange of the counter and the innersole without passing through the upper. It is 35 important that these tacks, which may be termed counter-flange tacks, be driven at predetermined distances from the last edge, notwithstanding variations in width of the lasts and preferable that they should be so 40 located and driven automatically.

An important feature of this invention consists in means for insuring that the counter flange tacks be always inserted at predetermined distances from the last edge, 45 irrespectively of the width of the last. As shown herein, the flange tackers and shoe are relatively movable to position the tackers over the heel seat of the shoe, and the tackers are relatively moved automatically 50 outwardly of the heel seat to positions such that the tackers on opposite sides of the heel seat are at predetermined distances from the last edge. The tackers are preferably positioned near together during their movement

of advance over the heel seat so that they 55 will more readily pass beyond the upstanding margin of the upper at the rear of the shoe and are then separated to their tack driving positions. The separation of the tackers is preferably effected by mechanism 60 which is positioned in accordance with a dimension of the shoe and which calipers, for example, the width of the shoe, the caliper mechanism co-operating with means on the tackers during their movement 65 of advance over the shoe bottom to cause them to separate until they are located at predetermined, constant, and preferably equal distances from the opposite edges of 70 the last bottom.

In the machine of the prior patent referred to above the counter tackers, after they have advanced over the shoe into tack driving position, are out of contact with the work, there being a space between the ends of the tacker nozzles and the flange of the counter. The tacks, therefore, have to 75 be driven "through the air". As a consequence the points of the counter tacks sometimes shoot sideways and the tacks are 80 therefore not driven straight into the work.

Another feature of the present invention consists in means for insuring that the counter tack mechanisms have their tack nozzles or holders moved toward the work before the tacks are driven. As herein shown, the tack holders are mounted for limited movement toward the work, and means operated by movement of the tack drivers in the early part of their descent is 85 provided to move the tack holders into contact with the work in advance of the action 90 of the drivers to drive the tacks through the tack holders into the work. In the illustrated embodiment of the invention this movement of the tack holders is effected 95 yieldingly through suitable springs.

In the machine shown in the patent above referred to, mechanism including a fixed lower abutment is provided for rigidly 100 clamping the shoe upper against the cone of the last at a point remote from the last bottom while the margin of the upper extending above the bottom of the last is seized and tensioned over the heel seat as the wiper advances. It is desirable that the lower abutment accommodate itself to different 105 sizes and shapes of lasts so that they will

be properly positioned in the machine for the action of the gripper, wipers, and other operating mechanism without attention of the operator and without his taking time to 5 make adjustments.

Another feature of the present invention consists, therefore, in means by which the lower abutment is rendered self-adjusting to lasts of different sizes and shapes, and 10 means by which the abutment, after the last has reached a predetermined position in the machine, is rendered unyielding to permit the last to be clamped in the machine by rearwardly directed pressure. As shown 15 herein, the lower abutment is mounted for movement longitudinally of the shoe, and the upper abutment is similarly mounted, mechanism being provided for rendering the lower abutment unyielding when the upper 20 abutment is moved rearwardly or inwardly.

It is important that the margin of the upper at the rear of the heel seat be properly located between the end of the wiper and 25 the gripper which co-operates with it to seize the upper margin before the machine is started. In the normal operation of the machine the shoe is lowered as it is swung into the machine, and after the upper passes 30 the gripper the shoe is raised and the gripper is positioned directly inside the margin of the upper and against the heel seat or flange of the counter and is carried with the shoe as the shoe is pushed farther into the 35 machine.

Another feature of the invention consists in the combination with gripping means and operating means therefor, of means for rendering the operating means inoperative until 40 the gripping means has been closed upon the stock. The gripping means may comprise a wiper and a gripping element co-operating therewith, the mechanism being organized to prevent movement of the gripping element 45 by the operating means unless the gripping element is moved toward the wiper and into proximity to the wiper in position to do its work. This mechanism prevents the machine from being started until the gripper 50 is properly located relatively to the upper which it is to seize and the shoe is properly positioned in the machine.

It is also important that the width of 55 the foxing, or of the vamp when a whole vamp is used, from the seam uniting the foxing and quarter to the heel seat be constant in shoes of a given style. Accordingly, a feature of the invention consists in means for positioning the shoe vertically with the 60 seam uniting the quarter and foxing at a predetermined distance from the plane in which the wiper acts, so that by relative adjustment of the upper and the last the amount wiped over upon the heel seat may 65 be varied to maintain the width of the fox-

ing from the seam to the heel seat constant.

These and other features of the invention will appear more fully from the following detailed description when read in 70 connection with the accompanying drawings and will be pointed out in the appended claims.

In the drawings,

Figure 1 is a side view of a machine 75 equipped with the present invention, the cam shaft being in section and the outer cam being omitted;

Fig. 2 is a front view of the head of the machine;

Fig. 3 is a perspective view of the upper and lower rear end abutments and the mechanism between them;

Fig. 4 is a detail of parts shown in Fig. 3;

Fig. 5 is a perspective view of the mechanism for preventing starting of the machine until the gripper is properly positioned;

Fig. 6 is a perspective view of the counter tacking mechanism;

Fig. 7 is a similar view on a larger scale 90 of parts illustrated in Fig. 6 and shows the parts in relation to a shoe being operated upon;

Fig. 8 is an exploded view of one of the counter tacking mechanisms;

Figs. 9 and 10 are plan views showing positions of the side clamps and drivers before and during their operations upon a shoe respectively; and

Fig. 11 is a detail showing the gage for 100 determining the width of the foxing.

In the drawings, the numeral 2 indicates the column of the machine near the base of which is pivoted at 4 a jack member 6 carrying a jack of the construction shown and 105 described in the above-mentioned patent. The shoe is placed upon a last pin 8 and swung toward the machine. A post 10 carrying the pin 8 is compressible against a light spring not shown. When the shoe 110 rises, after being depressed and moved toward the machine, the margin of the upper at the rear of the heel seat rises between a gripping element formed as a jaw 26 and a wiper 28. The wiper is shown in Fig. 6 115 and has corrugations or teeth adapted to co-operate with similar formations on the jaw 26.

During its movement toward the machine, the shoe first engages a lower abutment or 120 V-block 30 which is mounted to slide on a slight incline longitudinally of the shoe. Referring to Fig. 3, the V-block 30 is carried by a slide 31 having a T-guide 33 engaging a T-way 33 on a relatively fixed part 35 secured to the frame. Upon the rear end of the slide 31 is secured a block 32 on which is a ratchet plate 34 having rearwardly directed teeth 36. Below the plate 34 is mounted a pair of pawls 38 on a pin 40 which is sup- 130

ported by a bracket 42, fixed relatively to the slide 31. The portions of the pawls at the rear of the pivot 40 are formed with rectangular corners and are engaged by forks 44 (Fig. 4) having stems 46 extending loosely through holes in the lower end of a lever 48 pivoted to the part 35 between its ends at 50. Springs 52 are arranged on the stems 46 between the lever 48 and the forks 44. The upper end of the lever 48 is located in the path of a slide 53 upon which the upper abutment or V-block 54 is carried. The slide 53 is similar to the slide 31, is arranged for movement longitudinally of the shoe in a substantially horizontal direction and is held yieldingly toward the shoe by the springs 52, its forward movement being limited by a block 55 secured to the slide 53 and engaging the frame 35 in the forward position of the slide. When the rear end of the shoe engages the V-block 30 it is pushed rearwardly by the shoe, the pawls 38 being normally out of contact with the teeth 36. When the shoe reaches the upper V-block 54 and moves that rearwardly its inner end presses against the upper end of the lever 48, causing it to swing on its pivot 50 and its lower end to slide upon the stems 46 of the members 44. The point of contact of the lever 48 with the stems 46 is below the pivot 40 of the pawls 38, hence movement of the lever causes the pawls to swing into engagement with the teeth 36 and to lock the lower V-block against further inward movement. The pawls 38 differ in length an amount equal to one half the space between the teeth 36 and therefore act differentially to arrest the lower V-block. The upper V-block 54, however, is still yieldingly held by the springs 52.

As the shoe rises after being moved toward the machine, the gripper 26 constitutes a stop for limiting its upward movement, the upstanding margin of the upper at the rear of the shoe lying between the acting face of the gripper 26 and the front face of the wiper 28, the gripper resting preferably on the inwardly directed flange of the molded counter. As the shoe is pushed farther into the machine against the abutments 30, 54, the gripper 26 is moved inwardly with the shoe, being mounted to swing on a pivot 60 located considerably above the shoe bottom.

Mechanism responsive to this inward movement of the gripper is provided for preventing the machine from being started until the upper and gripper have been relatively positioned as described and the gripper moved toward the machine. This mechanism comprises a laterally extending arm 62 connected to the gripper 26 at one end and having its other end forked and adjustably connected to a rod 64 (Fig. 5). The adjusting means comprising a thumb nut 66 threaded on the rod 64 and carrying a sleeve 68 having a groove engaged by the forked end of the

arm 62 which is held in engagement therewith by a pin 63. The inner end of the rod 64 is pivotally connected to a latch 70 between its ends. The upper end of the latch 70 is pivoted at 72 to a vertically stationary part of the clutch mechanism. A projection 74 from the latch 70 is arranged to engage a stop pin 76 and is normally held against the pin by a spring 78. The lower end of the latch 70 is provided with an outturned flange 80 which lies normally under a block 82 clamped to a clutch operating rod 84 which leads to a starting treadle 86 (Fig. 1). The clutch may be of the type shown in United States Letters Patent No. 1,026,940, granted May 21, 1912, on application of Orrell Ashton, and is tripped by downward movement of a plate 88 connected to the rod 84. In Fig. 5 the parts are represented in the position they assume when the gripper 26 is in its inoperative position, away from the wiper and it will be evident that the clutch rod 84 cannot be moved downwardly to trip the clutch because of the engagement of the block 82 with the flange 80 on the latch 70. When the gripper is moved in with the work, as described, the arm 62 pushing on the rod 64 swings the latch 70 against the spring 78 until the flange 80 is clear of the block 82, whereupon the machine may be tripped as usual. With this type of clutch, the foot must be immediately removed from the treadle in order for the machine to stop at the end of a cycle. Consequently, the block 82 will be in raised position when the shoe is removed from the machine and the latch will, by outward movement of the gripper when the shoe is removed, reassume its position beneath the block 82 to prevent starting of the machine. The gripper is returned to its normal position by the spring 78.

The mechanism for operating the gripper 26 to force its lower end toward the wiper to grip the stock comprises an angle lever pivoted at 90 (Fig. 2) to a bracket 92 on the machine frame and having a laterally extending arm 94 carrying a screw 96 which projects inwardly through a clamp nut to engage the outer face of the gripper 26. The other arm 98 of the angle lever extends rearwardly and carries a cam roll 100 which co-operates with a cam formed on the inner face of a cam block 102. A spring 104 is connected between the machine frame and a hook 106 engaging over a rib on the upper side of the arm 94. The hook has a handle 107 by which it may be moved along the rib on the arm 94 to different distances from the fulcrum 90 of the lever so as to vary the force with which the upper is gripped. When the low portion of the cam 102 reaches the roll 100 the spring 104 is allowed to react, forcing the screw 96 on the arm 94 against the gripper 26 and causing it to hold the margin of the upper against the

advancing wiper so that the portion of the upper at the rear of the shoe which lies above the lower abutment 30 will be tensioned as the wiper and gripper move over the 5 shoe bottom.

The shoe having been positioned as described, the treadle 86 may be depressed to start the machine, whereupon a hook 110 co-operates with a roll 112 on the jack member 6, as is fully described in the first above-mentioned prior patent, to draw the shoe inwardly of the machine, lock it from downward movement, and clamp the portion of the shoe adjacent to the edge of the counter 15 which is most remote from the sole against the abutment 30 which has been locked against further movement in response to pressure of the shoe against the upper abutment 54 as described. As the hook 110 descends to lock the jack, one arm 116 (Fig. 1) of a bell-crank lever pivoted at 118 is released, causing the other arm 120 of the lever to permit inward movement of side 20 pressers 122, 124 under the influence of springs 126, all as described in the first above-mentioned prior patent. Referring to Fig. 10, which shows the side presses 122, 124 in operative position against the sides of the shoe, it will be seen that these 25 pressers are carried by arms 128, 130 which are mounted on rock shafts 131 and are moved toward the shoe by the springs 126 and serve to measure or caliper the width of the shoe across the heel seat portion.

30 Before the wiper 28 begins to advance, a tack is driven through the lower V-block or abutment 30 as described in the said first-mentioned patent, additionally to secure the upper already firmly held clamped against the last at that point.

The wiper and its operating mechanism are substantially as described in United States Letters Patent No. 1,204,928, granted November 14, 1916, on application of Orrell 45 Ashton, and need not be described in detail herein. After the driving of the tack through the lower abutment 30, the cam 102 allows the gripper to clamp the upper against the wiper in the manner described 50 and the wiper advances over the shoe bottom, thereby tensioning the upper at the rear of the shoe, and wiping it into place on the heel seat along the longitudinal median line of the heel, a tack supplied by a 55 tack tube 132 being driven by a central driver 134 when the wiper reaches its position of farthest advance over the shoe bottom. Mounted upon each side of the central driver 134 and carried by the wiper carrier 60 29 are two counter tacker frames 136, 138 which are mounted for movement laterally of the shoe bottom by bolts 139 which pass through holes 133 in tacker frames 136, 138 and through slots 137 in brackets 141 secured to the wiper carrier 29 (Fig. 7).

The bolts 139 are provided with spacing collars 145 (Fig. 8) which are longer than the thickness of the brackets 141 so that when the nuts of the bolts 139 are tightened, the bolts will still be free to move in the 70 slots 137. The tacker frames are held toward each other by a spring 143, as shown in Fig. 6. Tacks are supplied to these tackers by tack tubes 140, 142, and the tacks are driven by drivers 144, 146 having universal joint connection with a head 135 which also carries the driver 134 and is operated by a driver lever 174 in the usual manner. On the lower side of each of the tacker frames 136, 138 is a cam roll 150. The 75 cam rolls 150 are mounted on blocks 152 which are clamped upon flanges 155 on the lower portions 165 of the tacker frames by screws 154 as is best shown in Fig. 8. The rolls 150 co-operate with cams 156, 158 80 formed on the arms 128, 130 which carry, respectively, the side presses 122, 124. The position of the drivers and, of course, of the tackers before they begin to advance over the shoe bottom is indicated in Fig. 9. 85 As the tacker frames advance over the shoe bottom with the wiper, the rolls 150 engage the cams 156, 158 which are so shaped as to separate the tackers as they pass beyond the portion of the upper folded over by 90 the wiper and to position them at a predetermined distance from the last edge and, of course, from the shoe engaging faces of the 95 presses 122, 124. After the tackers have been fully separated, the direction of the 100 cam faces on the cams 156, 158 changes so as to be substantially parallel with the movement of the wiper, and the tackers are moved forward a short distance without being separated further. The final position of the 105 side tackers is indicated in Fig. 10 by the cross section of the drivers 144, 146. By loosening the clamp screws 154, the rolls 150 may be adjusted relatively to the tackers so as to vary the position of the tack 110 with respect to the edge of the last, and, if desired, to locate the tack on one side nearer to the edge of the last than on the other side. The tacks, however, are preferably driven equidistant from the edge of the last and 115 substantially midway of the inturned flange of the corner. The tacks supplied by the tack tubes 140, 142 are delivered to tack holders, each comprising two parts 160, 161 (Fig. 8) pivoted to a member 163 and held 120 together by a spring 162, so as to separate when the drivers descend to drive the tack held between them. The inner faces of the members 160, 161 are recessed and by separating the parts against the tension of the 125 spring 162 they may be assembled upon the projections 165 extending downwardly from each of the tacker frames above the flanges 155. The flanges 155 are so spaced from the tacker frames as to permit a limited 130

movement of the tack holders 160, 161 and of the members 163 which are pivoted to the tacker frames 138 by pins 164. Each tack holder is held in elevated position by 5 a spring 166 connected between the adjacent tacker frame and a pin 169. To each of the tack holder parts 160 is pivoted at its lower end a bar 168 by the pin 169. The bars extend upwardly along the tacker 10 frames and have at their upper ends laterally bent portions having holes through which pass respectively, the drivers 144, 146. Above the ends of the bars 168 are springs 170 surmounted by washers 142. When the drivers 15 144, 146 descend the head 135 carried by the driver lever 174 engages the washers 172, and compresses the springs 170 which push downwardly on the bars 168 overcoming the tension of the springs 166 and 20 forcing the tack holders into contact with the work. Excess downward movement of the tack holders 160, 161 when no shoe is in the machine is prevented by the flanges 155 or by the block 152 clamped thereon. This 25 downward movement of the tack holders insures that they will come in actual contact with the work and prevents liability of the point of the tack shooting sideways and being driven in an inclined position as sometimes happens when tacks are inserted "through the air", that is, from a tack holder which is slightly spaced from the surface of the work into which the tack is driven.

30 To maintain the width of the foxing from the foxing seam to the heel seat constant, a gage, shown in Fig. 11, is provided. The gage consists of a plate 180 having in its front end a V-shaped notch adapted to receive the rear portion of the shoe. The plate is dovetailed into the upper face of the lower V-block 30 for movement longitudinally of the shoe, this movement being limited by a pin 182 engaging a slot 184 in the plate. 35 The plate is maintained normally in forward position by a spring 186 seated in a bore in the V-block and arranged to engage the rear end of the plate. The plate normally has a position slightly in advance of the 40 face of the V-block and the shoe, as it is swung into the machine, is positioned with its rear end against the plate 180 and is allowed to rise until its heel seat is properly positioned by engagement with the gripper 45 26. The upper may then be adjusted downwardly or upwardly relatively to the last so that the lower edge of the foxing will engage the top face of the plate 180. In this way the width of the foxing in any 50 given style of shoe may be maintained constant. The V-blocks have the usual vertical adjustment by loosening the clamp nut 188 (Fig. 2) and turning the hand wheel 190 and therefore, the gage may be readily adjusted 55 vertically for different styles of shoes, or if

desired the lower V-block may be adjusted vertically relatively to the upper V-block by loosening a clamp screw operated by a handle 189, Fig. 2.

Mechanism is provided as usual for driving a tack into the rear portion of the shoe through the upper V-block 54 preferably simultaneously with the driving of the tacks into the heel seat of the shoe. The mechanism herein shown but not fully described 70 is equivalent to that shown in the prior patent first above-mentioned and will be readily understood by those skilled in this art. Tacks for the upper V-block 54 are supplied by a tack tube 191.

80 While the operation of the various mechanisms has been given in connection with the detailed explanation, it may be convenient briefly to recapitulate. The shoe materials are prepared for the assembling operation 85 by first securing a sole to the bottom of the last and placing over the last the upper materials comprising the lining and upper leather with a molded counter inserted between the lining and upper at the rear portion thereof. The upper is held to the last at the forepart by the hand of the operator and the shoe placed upon the spindle 8. The post 10 is depressed by downward pressure of the shoe and the shoe swung into the machine. The shoe is then allowed to rise and the upstanding margin of the upper passes between the gripper 26, and wiper 28, the 90 end of the gripper engaging the inturned flange of the counter. This locates the last 95 vertically and the upper is then pulled downwardly until the seam between the foxing and quarter engages the plate 180, thus measuring the width of the foxing. The shoe is then pushed against the V-block 30, 100 and being already in contact with the gripper 26 moves that inwardly of the machine and consequently moves the latch 70 out of operative relation to the block 82 so that the treadle may be depressed to start the 105 machine. The shoe after pushing the V-block 30 inwardly engages the V-block 54 and moves it inwardly, causing the pawls 38 to engage the teeth 36 and arrest further movement of the lower V-block 30. 110 The treadle is now depressed to start the machine. The hook 110 drops into engagement with the roll 112 to force the jack inwardly against the V-blocks and to clamp 115 the shoe rigidly against the lower V-block 30 and also locks the post 10 against downward movement. At the same time the side clamps 122, 124 are released and are forced by their springs 126 against the opposite sides of the rear portion of the shoe. The tack supplied to the lower V-block 30 by the tack tube 192 is now driven through 120 the block into the cone of the last to assist in holding the already clamped upper 125 against displacement during the upper ten- 130

sioning operation of the gripper, this tack being preferably used in addition to the clamping action of the post 10 which is forcing the last against the now rigid V-block 30. The cam 102 next allows the spring 104 to force the gripper 26 toward the end of the wiper firmly to grip the stock which lies between it and the wiper. The wiper now advances, tensioning the portion of upper between the lower V-block 30 and the gripper and wiping it over the heel seat of the shoe. The gripper preferably grips the upper firmly against the wiper and is timed by its cam 102 to release the wiper as soon as the wiper has passed over the shoe bottom far enough to obtain control of the upper and insure that the tension to which the upper has been subjected will be maintained by the pressure of the wiper against the heel seat. As the wiper advances the tacker frames 136, 138 are carried forwardly beyond the edge of the upper at the rear of the shoe and are separated by the action of the rolls 150 against the cams 156, 158 until the tack holders 160, 161 are located over the mid portion of the counter flange at each side of the heel seat and preferably at the corners of the heel seat, whereupon a tack is driven through each of the tack holders which are swung downwardly against the work about their pivots 164 prior to the insertion of the tacks by reason of the compression of the springs 170 during the downward movement of the drivers. A tack is driven also through the wiper 28 and through the overwiped upper as is indicated in Figs. 9 and 10. At the same time a tack may be driven if desired through the upper V-block. The driving of any one of the five tacks may, however, be discontinued or prevented by means shown and described in the above mentioned prior Patents No. 1,204,928 and No. 1,356,510. After the tacks are driven in the heel seat the wiper and its attendant tacking mechanism are raised out of contact with the work and retracted to normal position, the hook 110 is raised to free the jack and restore the side clamps to normal position, whereupon the machine stops, leaving jack free to be swung outwardly and the shoe removed.

Having fully described the invention, what I claim as new and desire to secure by Letters Patent of the United States is:

1. A machine for securing parts of boots and shoes in assembled relation upon a last preliminary to lasting having, in combination, tackers arranged for movement laterally of a shoe, and means controlled by the width of the shoe for effecting movement of the tackers laterally of the shoe.

2. A machine for securing parts of boots and shoes in assembled relation upon a last preliminary to lasting having, in combina-

tion, tackers positioned at the rear of a shoe, means for relatively moving the tackers and shoe a predetermined distance to position the tackers longitudinally of the shoe, and means controlled by the width of the shoe for effecting movement of the tackers laterally of the shoe.

3. A machine for securing parts of boots and shoes in assembled relation upon a last preliminary to lasting having, in combination, tackers, means for relatively moving the tackers and shoe to position the tackers over the shoe bottom, and means controlled by the width of the shoe for separating the tackers an amount proportioned to the width of the shoe.

4. A machine for securing parts of boots and shoes in assembled relation upon a last preliminary to lasting having, in combination, tackers positioned at the rear of a shoe, means for relatively moving the tackers and shoe a predetermined distance to position the tackers longitudinally of the shoe, and means controlled by the width of the shoe for separating the tackers an amount proportioned to the width of the shoe.

5. A machine for securing parts of boots and shoes in assembled relation upon a last preliminary to lasting having, in combination, tackers, means for relatively moving the tackers and shoe to position the tackers over the shoe bottom, and means for separating the tackers to position them at predetermined distances from the last edge irrespectively of the width of the shoe.

6. A machine for securing parts of boots and shoes in assembled relation upon a last preliminary to lasting having, in combination, tackers positioned at the rear of a shoe, means for relatively moving the tackers and shoe a predetermined distance to position the tackers longitudinally of the shoe, and means for positioning the tackers at predetermined distances from the last edge irrespectively of the width of the shoe.

7. A machine for securing parts of boots and shoes in assembled relation upon a last preliminary to lasting having, in combination, tackers movable transversely of the heel seat of a shoe, means for relatively moving the tackers and shoe to position the tackers over the shoe bottom, and means for separating the tackers to position them at predetermined distances from the last edge irrespectively of the width of the shoe.

8. A machine for securing parts of boots and shoes in assembled relation on a last preliminary to lasting having, in combination, means for holding the upper and last in assembled relation, means movable outwardly of the heel seat for securing the flange of the counter only to the heel seat at opposite sides of the heel seat, and

means for positioning the securing means at predetermined distances from the edge of the last notwithstanding variations in the width of the heel seats.

- 5 9. A machine for securing parts of boots and shoes in assembled relation on a last preliminary to lasting having, in combination, means for holding the upper and last in assembled relation, tacking means, means 10 for moving the last and tacking means relatively to position the tacking means over the heel seat, and means acting in consequence of said relative movement to position the tacking means inside the upper and 15 over the counter flange.

10. A machine for securing parts of boots and shoes in assembled relation on a last preliminary to lasting having, in combination, means for holding the upper and last 20 in assembled relation, tackers movable laterally of the last bottom, means for moving the last and tackers relatively to position the tackers over the last bottom, and means for separating the tackers an amount dependent 25 upon the width of the last to position the tackers at predetermined distances from the edge of the last bottom.

11. A machine for securing parts of boots and shoes in assembled relation upon a last 30 preliminary to lasting, having, in combination, means for holding the upper and last in assembled relation, means for securing the flange of the counter to the heel seat by fastenings which do not hold the outer thickness of the upper, and means for maintaining 35 the distance of said fastenings from the last edge constant irrespectively of variations in the sizes of the lasts.

12. A machine for securing parts of boots 40 and shoes in assembled relation upon a last preliminary to lasting, having, in combination, means for holding the upper and last in assembled relation, upon the last, means for securing the flange of the counter to the 45 heel seat, and means for positioning said securing means midway of the counter flange irrespectively of variations in the width of the heel seat.

13. A machine for securing parts of boots 50 and shoes in assembled relation upon a last preliminary to lasting, having, in combination, means for holding the upper and last in assembled relation, and means for securing the flange of the counter to the heel seat 55 at points equidistant from the edge of the last bottom, notwithstanding variations in the width of the lasts, by tacks which pass through the counter, lining and insole leaving the outer thickness of upper free.

60 14. A machine for securing parts of boots and shoes in assembled relation upon a last preliminary to lasting, having, in combination, means for holding the upper and last in assembled relation upon the last, means 65 for securing the upper and counter to the

heel seat, and means for further tacking the counter flange by tacks which pass through the counter, lining and innersole only, and means for maintaining the distance of said tacks from the last edge constant notwithstanding varying widths of different lasts.

70 15. A machine for securing parts of boots and shoes in assembled relation upon a last preparatory to lasting, having, in combination, shoe supporting means, a wiper movable over the rear portion of the heel seat, tacking means operating through the wiper to secure the wiper over upper to the heel seat, tackers carried by the wiper in advance 75 thereof to positions in front of the wiper and farther over the heel seat, and means for separating the tackers to locate them over the counter flange at the sides of the shoe.

80 16. A machine for securing parts of boots and shoes in assembled relation upon a last preparatory to lasting, having, in combination, a shoe support, a member arranged for reciprocation over the heel seat longitudinally of the shoe, tacking mechanism mounted on said member for movement transversely of the shoe bottom, the tacking mechanisms being normally near together so as to pass over the upstanding margin at 85 the rear of the shoe, and means for separating the tacking mechanisms to cause the tacks to be driven through the counter flange adjacent to the edge of the last bottom.

90 100 17. A machine for securing parts of boots and shoes in assembled relation upon a last preparatory to lasting, having, in combination, shoe supporting means, shoe clamping means adapted to engage a shoe on opposite sides of the rear portion adjacent to the plane of the heel seat, tackers arranged for movement over the shoe bottom and for movement laterally of the heel seat, and co-operating means upon the clamps and the 105 tackers whereby as they advance over the shoe bottom they are separated to position the tackers adjacent to the edge of the shoe bottom to insert the tacks through the counter flange, lining and innersole.

110 115 18. A machine for securing parts of boots and shoes in assembled relation on a last preliminary to lasting having, in combination, means for holding the upper and last in assembled relation, means arranged to be 120 positioned in accordance with the width of a shoe upon the last, tacking means movable laterally of the shoe, and connections between the tacking means and the positioning means to move the tacking means laterally in accordance with the width of the shoe.

125 130 19. A machine for securing parts of boots and shoes in assembled relation on a last preliminary to lasting having, in combina-

tion, means for holding the upper and last in assembled relation, means arranged to be separated in accordance with the width of a shoe upon the last, tacking means constructed and arranged to advance over the shoe bottom, and connections between the said separated means and the tacking means to separate the tacking means in proportion to the width of the shoe as determined by the said separated means.

20. A machine for securing parts of boots and shoes in assembled relation on a last preliminary to lasting having, in combination, means for holding the upper and last in assembled relation, two tackers movable relatively and movable together over the shoe bottom from a position behind the shoe forwardly, and means for moving the tackers relatively and determining automatically the amount of relative movement in accordance with the width of the shoe.

21. A machine for securing parts of boots and shoes in assembled relation on a last preliminary to lasting having, in combination, means for holding the upper and last in assembled relation, two tackers movable relatively and movable together over the shoe bottom from a position completely in the rear of the shoe forwardly, and means for moving the tackers relatively in conjunction with their forward movement to position the tackers over the flange of the counter.

22. A machine for securing parts of boots and shoes in assembled relation upon a last preliminary to lasting having, in combination, tackers positioned at the rear of a shoe comprising tack holding means, means for moving the tackers and a shoe relatively to position the tackers over the shoe bottom out of contact therewith, and means for moving the tack holding means into contact with the shoe bottom prior to the tack driving operation.

23. A machine for securing parts of boots and shoes in assembled relation upon a last preliminary to lasting having, in combination, tackers positioned at the rear of a shoe comprising tack holding means, means for moving the tackers to position the tackers over the shoe bottom out of contact therewith, and means operated by the drivers for moving the tack holding means into contact with the work.

24. A machine for securing parts of boots and shoes in assembled relation upon a last preliminary to lasting having, in combination, tackers positioned at the rear of a shoe comprising tack holding means, means for moving the tackers and the shoe relatively to position the tackers over the shoe bottom out of contact therewith, and means acting prior to the insertion of tacks for pressing the tack holding means into contact with the work.

25. A machine for securing parts of boots and shoes in assembled relation upon a last preliminary to lasting having, in combination, tackers positioned at the rear of a shoe comprising tack holding means, means for moving the tackers and the shoe relatively to position the tackers over the shoe bottom out of contact therewith, and means operated by the drivers in the early part of their descent for moving the tack holders into contact with the work.

26. A machine for securing parts of boots and shoes in assembled relation upon a last preliminary to lasting having, in combination, tackers positioned at the rear of a shoe comprising tack holding means and tack drivers, means for moving the tackers and shoe relatively to position the tackers over the shoe bottom out of contact therewith, springs for forcing the tack holding means against the work, and means for tensioning the spring during the movement of the drivers to drive the tacks.

27. In a machine of the class described, the combination of a reciprocating wiper, a gripper adapted to cooperate with the wiper in seizing the upstanding margin of the upper of a shoe, means for operating the gripper to seize the upper, and means for rendering said operating means inoperative until the gripper and wiper have been brought into predetermined position with respect to each other.

28. In a machine of the class described, the combination of a reciprocating wiper, a gripper adapted to cooperate with the wiper in seizing the upstanding margin of the upper of a shoe and movable by the work into proximity to the wiper, means for operating the gripper to seize the upper, and means for rendering the operating means inoperative unless the gripper has been moved by the work into proximity to the wiper.

29. In a machine of the class described, the combination of a wiper, a manually movable gripper, and means for preventing operation of the wiper unless the gripper has been moved toward the wiper.

30. In a machine of the class described, the combination of a gripper member adapted to engage the upstanding margin of the shoe upper, a wiper co-operating with the gripper member to seize the work and acting to wipe the gripped upper over the shoe bottom, and means for preventing operation of the wiper until the gripper has been positioned to do its work.

31. In a machine of the class described, the combination with a reciprocating wiper, a gripper adapted to co-operate with the wiper to seize the work and movable by the work toward the wiper, means for relatively operating the gripper and wiper to seize the upper, and means for rendering the opera-

tion of said operating means dependent upon the position of the gripper.

32. In a machine of the class described, a wiper for working over the upstanding margin of upper upon the heel seat of the shoe, a gripper arranged to co-operate with the wiper to seize and tension the upper during the wiping operation, and means for preventing operation of the wiper unless the gripper is brought into proximity to the wiper.

33. In a machine of the class described, the combination of a reciprocating wiper, a gripper adapted to co-operate with the wiper in seizing the upstanding margin of the upper of the shoe, power means for operating the wiper, and means responsive to control by the gripper for preventing power operation of the wiper until the wiper and gripper are in predetermined relative positions.

34. In a machine of the class described, the combination of a reciprocating wiper, a gripper adapted to co-operate with the wiper in seizing the upstanding margin of the upper of a shoe, a shoe support movable toward the machine and arranged for depression to enable the upper margin to be positioned behind the gripper and to yieldingly hold the shoe against the gripper so that the gripper will move with the shoe as the shoe is moved into the machine, and means permitting operation of the wiper only when the gripper has been brought into proximity with the wiper.

35. In a machine for securing the parts of boots and shoes in assembled relation on a last preparatory to lasting, the combination of means for supporting the shoe, means for positioning vertically a last on said support, means for positioning a shoe upper vertically on the last, and means to wipe over and secure to the heel seat the portion of upper projecting above the plane of the shoe bottom.

36. In a machine for securing the parts of boots and shoes in assembled relation on a last preparatory to lasting, the combination of means for supporting the shoe movable toward and from the machine, a gage on the machine constructed and arranged to engage the shoe beneath the edge of the foxing to locate the shoe upper vertically upon the last, and means to wipe over and secure the upper to the heel seat.

37. In a machine for securing parts of boots and shoes in assembled relation on a last preparatory to lasting, the combination of a vertically movable shoe support, means against which the shoe bottom is rested to determine its vertical position, and a gage arranged to contact with the edge of the foxing at the seam between the foxing and the quarter to determine the width of the

foxing, and means for securing the upper to the last.

38. In a machine for securing parts of boots and shoes in assembled relation on a last preparatory to lasting, the combination of a vertically movable shoe support, means against which the shoe bottom is rested to determine its vertical position, and a yielding gage arranged to contact with the edge of the foxing at the seam between the foxing and the quarter to determine the width of the foxing, and means for securing the upper to the last.

39. In a machine for securing parts of boots and shoes in assembled relation on a last preparatory to lasting, a shoe support, movable abutments for the rear end face of the last, means for holding one abutment yieldingly in position toward the shoe, and means operated by movement of the other abutment for rendering the first abutment unyielding in response to further pressure of the shoe.

40. In a machine for securing parts of boots and shoes in assembled relation on a last preparatory to lasting, a shoe support, a movable abutment for the rear end face of the last, means operated by contact with the shoe for locking the abutment against movement, and means for wiping over and securing the upper to the heel-seat.

41. A machine for securing parts of boots and shoes in assembled relation upon a last preliminary to lasting having, in combination, tackers positioned at the rear of a shoe comprising tack holding means, means for moving the tackers and a shoe relatively to position the tackers over the shoe bottom out of contact therewith, and means for moving the tack holding means toward the shoe bottom prior to the tack driving operation.

42. In a machine for securing parts of boots and shoes in assembled relation on a last preparatory to lasting, a shoe support, a plurality of abutments for the shoe arranged for movement by pressure of the shoe against them, and means for causing movement of one abutment to be arrested by movement of the other abutment.

43. In a machine for securing parts of boots and shoes in assembled relation on a last preparatory to lasting, a shoe support, a plurality of abutments for the rear end face of the shoe arranged for movement toward and from the shoe in different planes one above the other, and means operated by the upper abutment for arresting movement of the lower abutment.

44. In a machine for securing parts of boots and shoes in assembled relation on a last preparatory to lasting, a shoe support, a plurality of abutments for the rear end face of the shoe arranged for movement

toward and from the shoe, a pawl for arresting movement of one of the abutments, and connections from the pawl to another abutment for operating the pawl.

5 45. In a machine for securing parts of boots and shoes in assembled relation on a last preparatory to lasting, a shoe support, a plurality of abutments for the rear end face of the shoe arranged for movement toward and from the shoe in different planes one above the other, a pawl for arresting movement of the lower abutment, and connections from the pawl to the upper abutment for operating the pawl.

10 46. In a machine for securing parts of boots and shoes in assembled relation on a last preparatory to lasting, a shoe support, a plurality of abutments for the rear end face of the shoe arranged for movement toward and from the shoe in different relatively inclined planes one above the other, and means operated by one abutment for arresting movement of the other abutment.

15 47. In a machine for securing parts of boots and shoes in assembled relation on a last preparatory to lasting, a shoe support, a plurality of abutments for the rear end face of the shoe arranged for movement toward and from the shoe, and connections between the abutments for causing movement of one abutment to prevent movement of the other abutment.

20 48. In a machine of the class described, the combination of a plurality of movable tackers, means for moving the tackers simultaneously over a shoe bottom, and means for moving the tackers outwardly of the shoe bottom.

25 49. In a machine of the class described, the combination of a central tacker and lateral tackers, said tackers being movable together, means for moving the tackers together over the shoe bottom, and means for moving the lateral tackers outwardly of the shoe.

30 50. In a machine of the class described, the combination of a central tacker and lateral tackers constructed and arranged for movement together and relatively, and means for moving the tackers over a shoe bottom and for moving the lateral tackers relatively to the central tacker.

35 51. In a machine of the class described, the combination of a central tacker and a lateral tacker arranged for movement together and relatively, means for moving the tackers together over the shoe bottom, and means for moving the lateral tacker transversely of the shoe a distance proportional to the width of the shoe.

40 52. In a machine of the class described, the combination of a central tacker and lateral tackers, means for moving the tackers over the shoe bottom, and means for moving

the lateral tackers transversely of the path of the central tacker.

53. In a machine of the class described, the combination of a plurality of tackers and a shoe support relatively movable to cause the tackers to be positioned over the shoe bottom, means for separating the tackers to locate them near the edge of the shoe bottom, and means for operating the tackers.

54. In a machine of the class described, the combination of a plurality of tackers, a shoe support, means for relatively moving the support and tackers to position the tackers over the shoe bottom, means for separating the tackers to locate them over an inturned flange of upper material, and means for operating the tackers.

55. In a machine of the class described, the combination of a plurality of tackers, a shoe support, means for relatively moving the support and tackers to position the tackers over the shoe bottom, and means acting as an incident to said relative movement for separating the tackers to locate them over an inturned portion of shoe material.

56. In a machine of the class described, the combination of a plurality of tackers, a shoe support, means for relatively moving the support and tackers to position the tackers over the shoe bottom, and means acting as an incident to said relative movement for separating the tackers in accordance with the width of the shoe to locate the tackers adjacent to the edge of the shoe bottom.

57. In a machine of the class described, the combination of a plurality of tackers, a shoe support, means for relatively moving the support and tackers to position the tackers over the shoe bottom, and means acting as an incident to said relative movement for separating the tackers an amount determined by the width of the shoe and to locate the tackers in predetermined relation to the edge of the shoe bottom.

58. In a machine of the class described, the combination of a plurality of tackers and a shoe support relatively movable to position the tackers over the shoe bottom, means for separating the tackers to locate them over an inturned flange of upper material, and means for operating the tackers.

59. In a machine of the class described, the combination of a plurality of tackers, a shoe support, means for relatively moving the support and tackers to position the tackers over the shoe bottom, and means acting in conjunction with said relative movement for effecting a movement of separation of the tackers.

60. In a machine of the class described, the combination of a plurality of tackers, a shoe support, means for relatively moving the support and tackers to position the

- 5 tackers over the shoe bottom, means for caliperizing the shoe, and means controlled by the caliperizing means for separating the tackers in accordance with the setting of the caliperizing means.
- 10 61. In a machine of the class described, the combination of a plurality of tackers, a shoe support, means for relatively moving the support and tackers to position the tackers over the shoe bottom, means for caliperizing the width of the shoe, and means acting as an incident to said relative movement for separating the tackers an amount determined by the caliperizing means to locate the tackers in predetermined relation to the edge of the shoe bottom.
- 15 62. A machine for securing together the parts of boots and shoes upon lasts, having, in combination, tackers positioned at the rear of the shoe and comprising tack holding means, a work support arranged to permit relative movement of the tackers and shoe to position the tackers over the shoe bottom out of contact therewith, and means for 20 moving the tack holding means toward the shoe bottom prior to the driving of the tacks.
- 25 63. A machine for securing the parts of boots and shoes in assembled relation upon a last preliminary to lasting, having, in combination, a wiper movable over the shoe bottom, tackers movable with the wiper to locate the tackers over the shoe bottom inwardly of the counter flange, and means for 30 relatively moving the tackers to cause them to assume positions over the flange of the counter prior to the tacking operation.
- 35 64. In a machine of the class described, the combination of a cam shaft, a wiper movable over the shoe bottom, connections from the cam shaft to the wiper for operating the wiper, a gripper arranged to co-operate with the wiper to grip the upper, a gripper lever under the influence of a normally tensioned 40 spring for closing the gripper, and a cam on the shaft for controlling the action of the gripper lever.
- 45 65. In a machine of the class described, the combination of a cam shaft, a wiper movable over a shoe bottom, connections from the cam shaft to the wiper for operating the wiper, a gripper arranged to co-operate with the wiper to grip the upper, a gripper lever, a spring acting on the gripper lever 50 to close the gripper and a cam on the shaft for operating the gripper lever to tension the spring and to allow the spring to react to close the gripper.
- 55 66. In a machine of the class described, the combination of a last support, means engaging the lower edge of a shoe upper on the last to determine the amount of projection of the shoe upper above the last bottom,
- 65 means for clamping the upper to the last, and means for disposing the margin of upper extending above the last bottom parallel to the plane of the last bottom.
- 70 67. In a machine for shaping the rear portion of an upper to a last preliminary to lasting, a gage to engage an edge of the upper remote from the last bottom to determine its projection beyond the last bottom, means for applying pressure to the rear portion of the upper, and means for disposing the margin to the upper extending beyond the last bottom in a position parallel to the last bottom.
- 75 68. In a machine of the class described, the combination of a wiper movable inwardly of a shoe bottom, a tacker movable outwardly of the shoe bottom, and means for moving the tacker outwardly concurrently with the inward movement of the wiper.
- 80 69. A machine for securing parts of boots and shoes together having, in combination, a last support, a plurality of relatively movable tackers, means for effecting relative movement between the support and tackers, and means responsive to said relative movement for moving the tackers relatively to each other.
- 85 70. In a machine for assembling an upper of a shoe including a counter upon an inner-sole mounted on a last, a plurality of tackers, means for relatively moving the support and tackers to locate the tackers over the shoe bottom, and means responsive to said relative movement for relatively moving the tackers to locate them for insertion of tacks through the counter flange and innersole only.
- 90 71. In an assembling machine, means for securing an upper to a last, means for locating the last with respect to the securing means comprising a movable abutment engaging the rear end of the last adjacent to the cone of the last, a last support movable toward the abutment, and means in the path of the shoe and responsive to pressure thereof to arrest movement of said abutment when the shoe sole has reached a predetermined longitudinal position with respect to the securing means.
- 95 72. In a machine of the class described, a shoe support movable toward the machine, means for operating on the shoe requiring the shoe to be located in a predetermined position longitudinally with respect thereto, an abutment movable with the shoe as it is moved longitudinally toward the machine, and means responsive to said movement of the shoe to arrest the abutment when the shoe has reached the predetermined position with respect to the operating means.
- 100 In testimony whereof I have signed my name to this specification.
- 105 WILLIAM C. STEWART.
